(57) **CLAIM**

The ornamental design for a foldable gift bag, as shown and described.

DESCRIPTION

FIG. 1 is a top perspective view of the front side of a foldable gift bag showing my new design, wherein the upper sides of the foldable gift bag are shown in a folded position against the interior sides of the foldable gift bag;

FIG. 2 is a bottom perspective view of FIG. 1;

FIG. 3 is a side elevational view of FIG. 1, the opposite side being a mirror image thereof;

FIG. 4 is a front side elevational view of FIG. 1;

FIG. 5 is a top plan view of FIG. 1;

FIG. 6 is a bottom plan view of FIG. 1;

FIG. 7 is a top perspective view of the front side of the foldable gift bag, wherein the upper sides of the foldable gift bag are shown in an extended position;

FIG. 8 is a bottom perspective view of FIG. 7;

FIG. 9 is a side elevational view of FIG. 7, the opposite side being a mirror image thereof;

FIG. 10 is a front side elevational view of FIG. 7;

FIG. 11 is a back side elevational view of FIG. 7;

FIG. 12 is a top plan view of FIG. 7;

FIG. 13 is a bottom plan view of FIG. 7;

FIG. 14 is a top perspective view of the front side of the foldable gift bag, wherein the upper sides of the foldable gift bag are partially folded to thereby conceal the interior of the foldable gift bag;

FIG. 15 is a bottom perspective view of FIG. 14;

FIG. 16 is a side elevational view of FIG. 14, the opposite side being a mirror image thereof;

FIG. 17 is a front side elevational view of FIG. 14;

FIG. 18 is a back side elevational view of FIG. 14;

FIG. 19 is a top plan view of FIG. 14;

FIG. 20 is a bottom plan view of FIG. 14;

FIG. 21 is a top perspective view of the front side of the foldable gift bag, wherein the gussets of the foldable gift bag rest on the exterior lateral sides of the foldable gift bag;

FIG. 22 is a bottom perspective view of FIG. 21;

FIG. 23 is a side elevational view of FIG. 21, the opposite side being a mirror image thereof;

FIG. 24 is a front side elevational view of FIG. 21;

(Continued)

FIG. 25 is a back side elevational view of FIG. 21;
 FIG. 26 is a top plan view of FIG. 21; and,
 FIG. 27 is a bottom plan view of FIG. 21.
 The broken dashed lines (---) showing in FIGS. 1, 2, 4, 7, 8,
 10, 11, 14, 15, 17, 18, 21, 22, 24, and 25 are included for the
 purpose of illustrating an exemplary handle mechanism and
 handle neither of which forms a part of the claimed design.

1 Claim, 24 Drawing Sheets
